(57) **CLAIM**

I claim the ornamental design for a rotatable marble-sequesting skill game, as shown and described.

DESCRIPTION

FIG. 1 is a top perspective view of the rotatable marble-sequesting skill game of the present invention.

FIG. 2 is a bottom perspective view thereof.

FIG. 3 is a top plan view thereof.

FIG. 4 is a bottom plan view thereof; and,

FIG. 5 is a side elevation view thereof, all sides having the same features and appearance.

The drawing FIGS. 3-5 are drawn in an enlarged scale.

1 Claim, 3 Drawing Sheets

FIG. 3

FIG. 4

FIG. 5
